Primary Examiner — Phillip S Hyder*(74) Attorney, Agent, or Firm* — Foley & Lardner LLP(57) **CLAIM**

The ornamental design for a water closet, as shown and described.

DESCRIPTION

The present application is a broadening reissue of U.S. Pat. No. D621,918, which granted on Aug. 17, 2010, based on U.S. patent application Ser. No. 29/343,895, filed Sep. 21, 2009, the entire disclosure of which is incorporated herein by reference.

FIG. 1 is a right, top, front [perspective] isometric view of a water closet embodying our new design;

FIG. 2 is a right side elevational view thereof;

FIG. 3 is a left side elevational view thereof;

FIG. 4 is a front elevational view thereof;

FIG. 5 is a top plan view thereof;

FIG. 6 is bottom plan view thereof; and,

FIG. 7 is a rear elevational view thereof.

The broken line representations in the figures are for the purpose of illustration only, and form no part of the claimed design.

In a preferred embodiment, the nature of this product is a plumbing fixture in the form of a water closet, which is primarily useful for receiving the liquid and solid waste of humans.

1 Claim, 4 Drawing Sheets

Matter enclosed in heavy brackets [ ] appears in the original patent but forms no part of this reissue; matter printed in italics indicates the additions made by reissue.
